UNITED STATES PATENT OFFICE.

GUSTAF A. ANDERSON, OF BALTIMORE, MARYLAND, ASSIGNOR, BY MESNE ASSIGNMENTS, TO THE SYMINGTON COMPANY, A CORPORATION OF MARYLAND.

JOURNAL BOX.

Application filed December 4, 1922. Serial No. 604,764.

To all whom it may concern:

Be it known that I, GUSTAF A. ANDERSON, a citizen of the United States, residing at Baltimore, in the State of Maryland, have invented certain new and useful Improvements in Journal Boxes; and I do hereby declare the following to be a full, clear, and exact description of the invention, such as will enable others skilled in the art to which it appertains to make and use the same.

My invention relates to improvements in journal boxes especially adapted for use with truck side frames of the type set forth in my co-pending application, Serial No. 15 595,099, filed October 17, 1922, and of which my present invention is a continuation in part.

An object of my invention is to provide a journal box having portions shaped to conform to and arranged to engage portions of a car truck side frame, the particular shape of said portions permitting the use of a maximum amount of metal in the side frame at the critical points therein and also providing for the economical and efficient casting of the journal box in the mold.

Another object of the invention is to produce a journal box provided with a portion adapted to fit within a journal box recess in the side frame, said journal box being formed with means adapted to permit the journal box to be detachably connected to the side frame and maintained in bearing-like contact with the walls of said recess, said means involving longitudinally arranged lugs adapted to embrace the outer faces of the opposite side walls of the side frame and receive easily inserted connecting pins or bolts.

A further object of the invention resides in the provision of a journal box having inwardly and upwardly converging side walls suitably merged into the top of the journal box at different inclinations or angles, whereby in the manufacture of the journal box it will be possible to part the mold on a line passing through the center of the attaching lugs for that portion of the journal box at the front and rear of said lugs, and also permit of the portion of the side walls between the attaching lugs being shaped so that said portion, which is preferably cored in practice, is parted on a line below said first named parting line of the

mold, thereby affording greater cross sectional area to the adjacent side frame walls in which the journal box recess is formed.

A still further object of the invention is to provide a journal box possessing the advantages above noted, the interior of the journal box being maintained of a shape and size capable of receiving the standard equipment including the A. R. A. brass.

With these and other objects in view, the invention further consists in the combination and arrangement of the several parts, together with the method of manufacturing my improved journal box.

In the drawings illustrating the invention, the scope whereof is pointed out in the claims:

Figure 1 is a view partly in side elevation and partly in section of my improved journal box, the same being shown attached to a portion of the car truck side frame.

Figure 2 is a vertical sectional view taken transversely through the side frame showing my improved journal box with the upper portion engaging the journal box recess of the side frame, the car axle and other parts of the journal box being omitted.

Figure 3 is a top plan view of the journal box with parts in horizontal section, opposite portions of the side walls or abutments of the journal box recesses being shown in section with the attaching pins or bolts passing therethrough.

Figure 4 is a detail one-half horizontal sectional view on the line 4—4 of Figure 2, a portion of the brass and wedge being shown in position above the portion of the car axle illustrated.

Figure 5 is a fragmentary vertical sectional view on the line 5—5 of Figure 4.

Figures 6 and 7 are similar views on the lines 6—6 and 7—7 of Figure 4.

Referring to the drawings in which similar reference characters designate corresponding parts in the several views, my improved journal box 1 is shown attached to a truck side frame 2 preferably formed with an inner wall 3 and an outer wall 4. A journal box recess 5 is provided near each end of the side frame, said recess being provided with opposite abutment walls 6 and 7 which are inwardly and upwardly converged, said abutment walls being merged

into and united with the top wall 8 of the journal box recess. The wall portions of the side frame forming the journal box recess are preferably constructed from marginal inturned flanges 9 formed integrally with the side walls 3 and 4, said flanges being preferably united or abutted within the recess or immediately adjacent thereto by riveting or welding. I have described the foregoing type of side frame and journal box recess for a better understanding of my invention but it will be understood that my improved construction of journal box is capable of use with other types of truck side frames. In the present embodiment of my invention, however, I have shown the journal box associated with a journal box recess formed in the pressed metal side frame, the usual brass 10 and wedge 11 being fitted about the car axle within the journal box, all in the usual manner.

The journal box 1 is provided with side walls 12 united at their lower ends by the bottom 13 and at their upper ends by the top 14. Portions of the journal box are of the usual construction and may be provided with such parts as the journal box lid and dust-guard, not shown. The top wall portion 14 is preferably formed with a plurality of intersecting transversely and longitudinally disposed ribs 15 having their upper edges preferably shaped to conform to the contour of the upper wall 8 of the journal box recess. The end portions of the longitudinal or axially arranged ribs are shaped to extend about the corner bends which unite the side walls of the side frame with the marginal inturned edges thereof, as best shown in Figure 2. Lateral thrusts of the side frame with respect to the journal box are partly taken by the end portions of the ribs adjacent the aforesaid corner bends. The configuration of the journal box top forms a desirable bearing surface contacting the side frame and provides a strong construction of comparatively light weight.

The journal box is provided with means permitting its ready attachment to the truck side frame, said means including spaced longitudinally disposed lugs 16 and 17, said lugs embracing the respective inner and outer side walls of the side frame and each being provided with an opening 18. Registering openings 19 are provided in the side walls of the side frame and through the registering openings 18 and 19 connecting pins or bolts 20 are inserted, as clearly shown in Figure 3. Each pin 20 is provided at one end with a head 21, the opposite end of the pin being preferably perforated to receive the cotter 22. The pins 20 are preferably designed to fit loosely within the registering openings in the side walls and lugs, thereby permitting the longitudinal thrusts of the side frame to be principally

taken by the abutment walls 6 and 7 lining the journal box recess. The attaching lugs or projections provided on the journal box are preferably slightly spaced from the side walls of the side frame to provide clearance which, together with the relatively loose pin connections, permits any transverse thrusts occurring between the journal box and side frame to be effectively resisted.

The side walls of the journal box are provided with portions arranged to converge upwardly and inwardly at points to the front and rear of the journal box, the beginning of said convergence occurring on a line passing through the center of the pin openings 18 provided in the lugs 16 and 17. The inclinations or angles of these portions of each side wall are clearly shown in Figures 5 and 6, the horizontal line *a—a* passing through the center of the openings in the lugs indicating the parting line of the mold in which the journal box is cast for that portion of said journal box to the front and rear of the attaching lugs. Each side wall is provided with a portion between the attaching lugs, each portion being converged upwardly and inwardly, the beginning of said convergence being located in a horizontal plane below the parting line *a—a* passing through the center of the pin openings 18. The angle or inclination of this intermediate portion disposed between the attaching lugs is best shown in Figure 7, the line *b—b* indicating generally the beginning of the convergence of said portion at a point where this portion of the mold is separated. In practice it is usual to core out this portion of the casting between the attaching lugs, and it is because of this practice that the convergence of the side walls between the lugs can be lengthened with the advantage of permitting the use of a comparatively greater cross sectional area of metal in the pressed metal side frame between the outer journal box abutment wall 7 and the extreme end of the side frame. The increase of metal in the side frame blank at these points, which are some of the critical points of the side frame, is of great benefit in resisting the strains incident to service conditions.

My improved method of manufacturing a journal box of the class referred to consists in shaping portions of the side walls of the journal box so as to conform to the portion of the side frame with which the journal box contacts, said side wall portions being inwardly converged at their upper ends so as to provide for the use of a maximum quantity of metal in the side frame and at the same time permit the portions of the side walls at the front and rear of the journal box to be so shaped as to be easily cast in a mold which latter can be readily parted. It will also be noted that my improved

journal box is arranged for production in a mold capable of being parted on the center line of the attaching pin openings for that portion of the journal box which lies to the front and to the rear of the attaching lugs or projections. The portion of the side walls of the journal box between the attaching lugs is designed for parting below the line of the pin openings. This is desirable in practice in order to obtain the advantageous side frame construction referred to herein, and at the same time provide a construction which will not interfere with the molding of the journal box, because the portion between the pin lugs is preferably cored out, and the portions of the side wall outside of the pin lugs can be parted on the regular parting line of the mold which in my present embodiment is disposed in the same horizontal plane or center line passing through the pin openings.

I claim:

1. A journal box for railway cars having a top portion provided with a plurality of spaced ribs extending longitudinally of said box, said ribs having their upper faces adapted to conform to and engage a portion of a truck side frame, and side walls having their upper portions converging toward said top portion, said ribs and the converging portions of the side walls forming a bearing surface with which the side frame portions contact.

2. A journal box for railway cars having a top adapted to engage a portion of the truck side frame, and side walls arranged to contact other portions of said side frame, each of said side walls being formed with upwardly extending and inwardly converging spaced portions arranged respectively near the front and rear ends of the journal box, and having an intermediate upwardly extending and inwardly converging portion located between said spaced portions, the beginning of the convergence of said intermediate portion being located below the beginning of the convergence of said first named portions.

3. A journal box for railway cars having a front end and a rear end, and side walls adapted to contact portions of the truck side frame, each of said side walls having upwardly extending inwardly converging portions near said front and rear ends of the journal box and being provided with an intermediate upwardly extending and inwardly converging portion disposed at a different angle to said first named converging portions of the side frame.

4. A journal box having front and rear ends, and side walls having their upper portions inwardly inclined to the vertical, the angle of inclination varying at points intermediate the front and rear ends of the journal box.

5. A journal box for railway cars, said box having opposite side walls, means extending from the side walls for attaching the journal box to a car truck side frame, an intermediate converging portion provided on each side wall adjacent said attaching means, the beginning of the convergence of said intermediate portion being located below the horizontal center of the attaching means, and adjacent converging portions formed in each side wall, said last named converging portions having the beginning of their convergence located in a plane passing through the horizontal center of said attaching means. 70

6. A journal box for railway cars having a portion adapted to engage a truck side frame, side walls arranged to contact other portions of said side frame, each of said side walls being provided with an intermediate converging portion adapted to permit the use of a maximum cross sectional area of metal in the side frame adjacent the journal box, and having converging portions adjacent said intermediate converging portion, said last named converging portions having the beginning of their points of convergence located above the beginning of the point of convergence of said intermediate converging portion. 85

7. A journal box for railway cars having a portion adapted to engage a truck side frame, side walls arranged to contact other portions of said side frame, projections carried by said journal box and adapted to embrace the side frame, portions of each of said side walls being inwardly converged at their upper ends between said projections and other portions of each of said side walls being inwardly converged at 105 their upper ends outside of said projections.

8. A journal box for railway cars having a portion adapted to engage a truck side frame, side walls having inwardly converging portions adapted to contact other portions of said side frame, and means including a plurality of pairs of laterally extending lugs carried by said journal box and overlapping the adjacent portions of said side frame for connecting the journal box 110 thereto.

9. A journal box for railway cars having a portion adapted to engage a truck side frame, side walls having inwardly converging portions adapted to contact other portions of said side frame, and means including longitudinally arranged lugs carried by said journal box for connecting the same to the side frame, each of said lugs being provided with an opening, the center of which forms the parting line of the mold in which the journal box is cast for that portion of the journal box to the front and rear of said lugs. 120

10. A journal box for railway cars hav- 130

ing a top portion adapted to engage a truck side frame, inwardly converging side wall portions also arranged to contact other portions of said side frame, and a plurality of lugs extending from each of said side walls, said lugs being adapted to be connected to said side frame.

11. A journal box for railway cars having a top portion adapted to engage a truck side frame, inwardly converging side wall portions also arranged to contact other portions of said side frame, and a plurality of pairs of attaching lugs formed on said side walls and adapted to embrace the side frame.

12. A journal box for railway cars having a top portion provided with a plurality of longitudinally extending ribs, the upper faces of which being adapted to conform to a portion of a truck side frame and form a bearing contact therewith, and side walls arranged to contact other portions of said side frame, each of said side walls having an inwardly converging upper portion united with said ribbed top portion and adapted to form a continuous bearing surface for contacting the truck side frame.

13. A journal box for railway cars having a top portion provided with a plurality of longitudinally extending ribs, the upper faces of which being adapted to conform to and form a bearing contact with a portion of the truck side frame, the opposite ends of some of said last named ribs being adapted to contact the opposite outer faces of the truck side frame.

14. A cast metal journal box having a plurality of pairs of side frame attaching portions and having inwardly and upwardly converging opposite side wall portions intermediate each pair of attaching portions the beginning of the convergence of

the side wall portions lying in a plane below the center of said attaching portions, said plane forming a parting line for at least a portion of the mold in which the journal box is cast.

15. A cast metal journal box having a plurality of inwardly converging portions on each side wall thereof, the point of convergence of one portion lying in one horizontal plane and the point of convergence of another portion lying in another horizontal plane, thereby providing a plurality of parting lines for the mold in which the journal box is cast.

16. A cast metal journal box having side frame attaching portions and having inwardly and upwardly converging opposite side walls the convergence of said side walls between the attaching portions and the ends of said journal box lying in a plane passing through the center of said attaching portions, said plane forming the parting line of the mold in which the journal box is cast.

17. A cast metal journal box having a plurality of spaced pairs of side frame attaching portions and having inwardly and upwardly converging opposite side walls the convergence of said side walls between said attaching portions and the ends of said box lying in a plane passing through the center of said attaching portions, the convergence of the portions of said side walls between said attaching portions lying in a lower horizontal plane whereby the intermediate portion of each side wall is upwardly and inwardly converged from a point below the beginning of said first named convergence.

In testimony whereof I affix my signature.

GUSTAF A. ANDERSON.
